ARTHUR P. BROCKLEBANK, OF ELIZABETH, NEW JERSEY, ASSIGNOR TO FOSTER WHEELER CORPORATION, OF NEW YORK, N. Y., A CORPORATION OF NEW YORK.

HEAT EXCHANGER.

Application filed November 5, 1927. Serial No. 231,204.

This invention relates to a heat exchanger of the type in which there is commonly employed a shell, a plurality of tubes therein, and means for passing mediums, to and from which heat is to be added or extracted to the space in the shell surrounding the tubes and through the spaces within the tubes. The heat exchanger is, furthermore, of the type adapted for use in the petroleum industry or 10 as surface condensers, feed water heaters and the like in power plant practice.

In certain types of heat exchangers of the kind to which the invention relates, it is customary to divide the interior of the shell into a plurality of compartments by employing a longitudinally disposed baffle plate or baffle plates dividing the tubes into banks for the purpose of directing the flow of the medium passing through the shell of the apparatus to cause the same to come into intimate contact with as much as possible of the tube surface therein. Heretofore, difficulty has been experienced in making a joint between the baffle plate and the shell sufficiently tight to prevent a portion at least of the medium from leaking or by-passing from one compartment to another within the shell and thereby not following its intended course and consequently impairing the efficiency of the apparatus.

30 The present invention, therefore, relates more particularly to the form of joint in this type of heat exchanger between the baffle plate or partition wall and the shell with the object of overcoming the difficulties to which 35 reference has been made by providing a substantially tight joint between the baffle plate and the shell thereby positively causing the medium flowing through the shell to follow its intended course and to thereby increase the 40 efficiency of the apparatus as far as may be possible by preventing the leakage or bypassing of the medium from one compartment to another within the shell as will be herein-after more particularly described.

45 In the drawing Figure 1 is an elevation of the partial section of the heat exchanger in which the present invention is incorporated.

Figure 2 is a partial transverse section on an enlarged scale illustrating a form of joint 50 between the baffle plate and shell.

Figure 3 is a section on line 3—3, Figure 2. Figure 4 is a view similar to Figure 2 showing another form of the invention.

Figure 5 is a central longitudinal section on

an enlarged scale showing another form 55 of joint,

Figure 6 is a section on line 6—6, Figure 5 on an enlarged scale and

Figure 7 is a view similar to Figure 6 showing still another form of the joint.

Referring to the drawing the heat exchanger, in which the present invention is incorporated, is illustrated as including a shell 10, which is preferably cylindrical, but may be of other configuration, and is provided at its 65 extremities with flanges 11 and 12. The shell is also provided in suitable places with an inlet nozzle or connection 13 and an outlet nozzle or connection 14. At one end of the shell there is a tube plate 15 and at this end thereof the shell is fitted with a box for the inlet and discharge of a medium. This box 16 as illustrated is provided interiorly with a partition 70 wall 17 extending transversely across the same and in oppositely disposed positions the 75 box 16 is made with an inlet nozzle or connection 18 and an outlet nozzle or connection 19 whereby the box serves as an inlet and an outlet for the medium passing to and from the same. It will be understood that the box 16 is suitably flanged or otherwise provided with 80 means whereby the box and the flange 12 of the shell may be suitably connected with the tube plate 15 intervening. At the opposite 85 end of the shell the same is fitted with a cover 20, which is connected to the flange 11 of the shell by any suitable means. Within the cover 20 or at this end of the shell, there is a tube plate 21 within the shell, and extending between and connected to the tube 90 plates there are the usual tubes indicated at 22. The tube plate 21 and a bonnet 23 connected thereto are preferably of the floating head type.

The shell may be divided interiorly into a 95 plurality of compartments. For the purpose of illustration the shell is shown as being divided into two compartments by a single baffle member. Of course, when there is a greater number of compartments in the shell a correspondingly greater number of baffle or partition walls must be employed, but these baffles and walls and the joints between the same and the shell are similarly made and for this reason the illustration and description of one of these baffles or partition walls 100 and the joint between the same and the shell 105 will serve for explaining the construction.

thereof. In carrying out the invention the baffle or partition wall preferably comprises a pair of plates indicated at 24 and 25 although, of course, the number of plates is not so limited. As illustrated, these plates adjacent the long edges are separated by a spacer bar 26 to which they are connected and maintained in this spaced position by bolts or rivets 27 or otherwise. The shell of the apparatus is interiorly fitted with oppositely disposed rails, one of which for the purpose of illustration is indicated at 28. These rails are secured to the shell in any suitable manner and serve as supports for the baffle or partition wall, the parts being so designed that the width of the rails is substantially equal to the distance between the inner or adjacent faces of the plates 24 and 25 of the baffle, whereby the baffle is adapted to slide to position on these rails. It will, furthermore, be understood that due to the floating head tube plate construction, this baffle is removable with the tube plate 15, the tubes and the floating head as a unit.

In order to provide a tight joint between the edges of the plates 24 and 25 and the rail 28 I employ a strip of packing 29. This may be made of any suitable material, such, for example, as asbestos or the like. In order to maintain the packing against the face of the rail and also against the adjacent portion of the inner faces of the plates of the baffle, I employ a packing strip 30 of metal or similar material, which in length is co-extensive with the rail and is maintained in position against the packing by a series of springs or other equivalent means which are resilient or otherwise. As illustrated, for example, in Figures 2 and 3 of the drawing, I may employ a plurality of suitably spaced springs 31, each spring being fixed in position to the spacer bar by means of rivets or bolts 32 or otherwise. By the use of the packing, the packing strips, and the springs it will be understood that the packing strip is yieldingly maintained in position against the packing, which forces the packing in place against the rail and against the inner faces of the plates forming the baffle in order to make a tight joint between these parts.

In some instances where there may be considerable pressure employed in forcing the medium through the compartments of the shell, the packing, as indicated at 33 in Figure 4, may be considerably thicker than that indicated in Figures 2 and 3, and may be recessed on one side as indicated at 34, the wall defining the recess being tapered to receive the corresponding tapered walls 35 of the packing strip 36. These parts are maintained in position by means of springs or other similar devices, as hereinbefore described, and due to the tapering walls, the packing strip, and the recess in the side of the packing, the packing is not only forced against the inner face of

the rail 28 but the edges of the packing are more forceably maintained in position against the inner faces of the plates 24 and 25 forming the baffle.

In other instances it may be possible to dispense with the rails 28 and also with the springs as a holding means for maintaining the packing in position, for example, as shown in Figures 5 and 6, the plates 38 and 39 forming the walls of the baffle may be connected and spaced by the spacer bars 40 to which these plates are connected by rivets or bolts 41 or otherwise. In this construction the inner face of the spacer bar 40 is tapered from end to end, as indicated at 42, and a wedge 43 having a correspondingly tapered face employed to force the packing 37 to position directly against the inner surface of the shell of the apparatus. It will be understood that by suitable means the packing and the wedge member may be placed in position after the tube bundle is inserted in the shell.

In other instances the rails 28 may also be dispensed with, as illustrated in Figure 7, and the packing maintained in position directly in contact with the inner surface of the shell. For example, in this construction, the baffle comprises plates 44 and 45, suitably spaced and maintained in their relative relationship by the spacer bar 46 and rivets or bolts 47. Connected to the spacer bar there is a series of springs, one of which is indicated at 48 and all of which are adapted to bear against a packing rail 49 to force and maintain a packing 50 against the inner surface of the shell as hereinbefore stated. It will be understood that in so doing this packing is also forced against the adjacent inner surface of the plates 44 and 45 to thereby complete a substantially tight joint between the parts of the baffle and the inner wall of the shell.

It will be understood that the forms of the invention herein shown and described are more or less illustrative as these and equivalent forms may be employed without departing from the nature and spirit of the invention which involves suitable means for positively forcing and maintaining a packing in position to produce a substantially tight joint between a baffle plate and the shell of a heat exchanger apparatus.

I claim as my invention:

1. In a heat exchange apparatus, a shell, tube plates, tubes extending between the tube plates, a baffle extending longitudinally of the shell and dividing the same into compartments, a packing at the longitudinal edge of the baffle, and means for positively forcing the packing to position to make a substantially tight joint between the shell and the baffle.

2. In a heat exchange apparatus, a shell, tube plates, tubes extending between the tube plates, a multipart baffle extending longitudinally of the shell and dividing the same

- interiorly into compartments, a packing, and means for positively forcing the packing to position between the parts of the baffle to form a substantially leak proof joint between the shell and the baffle. 5
3. In a heat exchange apparatus, a shell, tube plates, tubes extending between the tube plates, a two part baffle dividing the shell longitudinally into compartments, means for spacing the parts of the baffle, a packing, and means for forcing the packing to position between the parts of the baffle and the shell to make a substantially leak proof joint between them. 10
- 15 4. In a heat exchange apparatus, a shell, tube plates, tubes extending between the tube plates, a rail secured interiorly to the shell and extending longitudinally thereof, a multi-part baffle extending longitudinally of the shell and dividing the same into compartments and adapted to engage the said rail, a packing lying within the parts of the baffle, and means for forcing the packing to position against the rail and the parts of the baffle to make a substantially leak proof joint between them. 20
- 25 5. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 30
- 35 6. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a packing within the edge portion of the said baffle, and means for forcing the packing against the baffle with the adjacent portion of the rail to make a substantially leak proof joint between them. 40
- 40 7. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar to which the parts of the baffle are secured, a packing, and means co-operating with the spacer bar for forcing and maintaining the packing in position against the said rail and the adjacent parts of the baffle for making a substantially tight joint between them. 45
- 50 8. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 55
- 55 9. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 60
- 65 10. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 65
- 70 11. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 75
- 75 12. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 80
- 80 13. In a heat exchange apparatus, a shell, tube plates, tubes extending between the tube plates, a rail secured interiorly to the shell and extending longitudinally thereof, a two part baffle also extending longitudinally of the shell, dividing the same into compartments, and adapted at an edge portion to span and engage the said rail, a spacer bar, a packing lying between the edge portions of the baffle, a packing rail adjacent the said packing, and means co-operating between the spacer bar and the packing rail for forcing and maintaining the packing in position against the said rail and the adjacent parts of the baffle to form a substantially leak proof joint between them. 85

Signed by me this 5th day of October, 1927.

ARTHUR P. BROCKLEBANK.
